(57) **CLAIM**

The ornamental design for a nasal dilator, as shown and described.

DESCRIPTION

FIG. 1 is a perspective view of a first embodiment of a nasal dilator showing my new design;

FIG. 2 is a top plan view thereof;

FIG. 3 is a front view thereof, the rear view being a mirror image;

FIG. 4 is a right side view thereof, the left side view being a mirror image;

FIG. 5 is a bottom plan view thereof;

FIG. 6 is a perspective view of a second embodiment of a nasal dilator showing my new design;

FIG. 7 is a top plan view thereof;

FIG. 8 is a front view thereof, the rear view being a mirror image;

FIG. 9 is a right side view thereof, the left side view being a mirror image;

FIG. 10 is a bottom plan view thereof;

FIG. 11 is a perspective view of a third embodiment of a nasal dilator showing my new design;

FIG. 12 is a top plan view thereof;

FIG. 13 is a front view thereof, the rear view being a mirror image;

FIG. 14 is a right side view thereof, the left side view being a mirror image;

FIG. 15 is a bottom plan view thereof;

FIG. 16 is a perspective view of a fourth embodiment of a nasal dilator showing my new design;

FIG. 17 is a top plan view thereof;

FIG. 18 is a front view thereof, the rear view being a mirror image;

FIG. 19 is a right side view thereof, the left side view being a mirror image; and,

FIG. 20 is a bottom plan view thereof.

The broken line showing of human facial features is directed to environment and is for illustrative purposes only; the broken lines form no part of the claimed design.
